UNITED STATES PATENT OFFICE

165,109

DISPENSING BRUSH FOR BOTTLES

Stanley Petrosky, National City, Calif.

Application April 5, 1951, Serial No. 14,716

Term of patent 7 years

(Cl. D9—2)

To all whom it may concern:

Be it known that I, Stanley Petrosky, a citizen of the United States, residing at National City, in the county of San Diego and State of California, have invented a new, original, and ornamental Design for a Dispensing Brush for Bottles, of which the following is a specification, reference being had to the accompanying drawing, forming part thereof.

Fig. 1 is a bottom perspective view of a dispensing brush for bottles, showing my new design.

Fig. 2 is a front elevational view thereof.

Fig. 3 is a right hand elevational view thereof.

Fig. 4 is a section on line 4—4 of Fig. 2.

I claim:

The ornamental design for a dispensing brush for bottles, substantially as shown.

STANLEY PETROSKY.
